PIPE CLEANER

Claes Axel Klingenstierna, Karlstad, Sweden

Application December 24, 1946, Serial No. 718,187
In Sweden January 25, 1946

6 Claims. (Cl. 131—243)

1

The present invention relates to a utensil for cleaning, filling, boring and drying tobacco-pipes. The utensil consists of two parts, a tubular casing and a needle member which can be used both separately and in combination.

The chief object of this invention is to create a utensil which is very useful for cleaning and drying tobacco pipes, and also for boring and drying such pipes.

Another object of this invention is to create the two parts of the utensil in such manner that when used either in combination or singly these two parts excellently fill all the demands that can be made upon a utensil of the said kind. At the same time they are very simple and cheap in manufacture and can easily be carried in the pocket after the needle has been inserted into the casing.

Other objects will be evident from the following specification and claims.

An embodiment of the utensil according to the invention is shown in the accompanying drawing in which

Fig. 1 is a perspective view of the needle showing the positions of the shanks when the needle has been removed from the casing.

Fig. 2 shows a side view of the tubular casing with the needle inserted therein.

Fig. 3 shows a part of a modified embodiment of a shank of the needle.

Fig. 4 is a perspective view of a modification of the tubular casing.

Fig. 5 shows a cross-section on the line V—V in Fig. 2 with the needle omitted.

Fig. 6 shows a cross-section on the line VI—VI in Fig. 4.

Referring now to Figs. 1, 2 and 5 of the drawing the reference numeral 1 designates a casing which consists of a tube open at both ends and preferably made of metal. At both ends the casing is provided with flanges 2 and 2a, the flange 2a being preferably somewhat larger than the flange 2. The tube should have a length substantially equal to the total length of the stem and the pipe neck of a tobacco-pipe. The needle member 3 is somewhat longer than the casing 1 and is made of a resilient wire bent to form three shanks 4, 5, and 6. The shanks 4 and 5 are formed by the free ends of the wire, while the shank 6 has been formed by double-folding the middle portion of the wire, one part of the shank 6 having been wound into turns around the other part at 6A. The bends of the wire as well as the winding 6A are made in such a manner that the shanks diverge strongly. The double shank 6 is

2

provided with a bend 7 and at its free end the shank 4 is provided with a bent 8 or flattened portion 8a as shown in Fig. 3. The thickness of the wire is so chosen that the shanks 4 and 5 can be inserted at the same time into the smoke passage of a tobacco-pipe.

When the pipe neck and the stem are to be cleaned, the needle 3 is pushed out to the required length from the tube 2. Because the shanks tend to spring apart, the needle 3 is safely held in the casing 1 in its pushed out position. If the whole length of the needle must be utilized, the needle is completely pushed out from the casing. If necessary, the needle may be extended by straightening out one or both shanks 4, 5 so that the same will be in line with the double shank 6. The pipe may be cleaned by inserting one or more of the shanks into the pipe neck and the stem respectively. The double shank possibly together with one or both of the simple shanks is substantially intended for cleaning the pipe neck, while the simple shanks, either individually or jointly, are intended for cleaning the pipe stems.

If the pipe bowl is to be cleaned or bored, that flange 2 or 2a should be chosen which best suits the size of the pipe bowl. The flange has a suitable edge for removing slag and deposits from the pipe bowl. Such slag which has stuck in the opening of the casing 1 during the cleaning may be removed by pushing out the needle. The bottom of the pipe bowl and the channel in the pipe stem are cleaned by means of the needle 3 preferably using the casing 1 as a handle. The pipe bowl may at the same time be dried by use of the shank points after heating them over the flame of a match or the like. When a foul pipe is to be dried more heat is required and then the end of the casing may be used for the drying after the end of the casing has been heated over a gas-flame or the like. Owing to the great length of the casing it is then possible to hold its opposite end in one's hand without burning the fingers.

In order to obtain a suitable, concave, somewhat open tobacco filling in the pipe when filling the same the bent end of the needle 3 should be moved to a level with one of the edges of the casing 1. When now the tobacco put in the pipe is pressed down into the bowl by means of the casing 1, this filling will be hard compressed at the edges of the pipe bowl but less hard in the center. This is advantageous both when lighting the pipe and for getting an even combustion. Of course, the casing may be given any suitable form in cross section, preferably circular as shown in Figs. 2 and 5, or elliptic, as shown in Figs. 4 and 6.

These figures also illustrate an embodiment, in which the flanges *2c* and *2d* are unsymmetrical, thus rendering a better cutting action when the casing is turned round in the pipe bowl.

Fig. 3 shows that one free end of a shank may be provided with a flattened portion *3a*.

Having now described my invention, what I claim as new and desire to secure by Letters Patent is:

1. A utensil for tobacco-pipes comprising a tubular, relatively thin-walled casing open from end to end and provided with integral flanges at both ends, said flanges being in the form of funnels and of different sizes, and a needle insertable and adjustable in said casing, said needle being longer than the casing and covered by the latter for substantially its entire length, and having at least three shanks, said shanks being individually resiliently spaced apart in such a manner that the needle is maintained in any arbitrary position in the casing, said needle consisting of an integral resilient wire, the end portions of the needle constituting the two outer shanks, the intermediate shank being a double-folded portion of the wire, the elements of said double-folded portion lying close to one another, each of said shanks diverging in a different direction, and one of the elements of the double-folded shank being fixed to the other element for a portion of its length.

2. A utensil for tobacco-pipes comprising a tubular, relatively thin-walled casing open from end to end and provided with integral flanges at both ends, said flanges being in the form of funnels and of different sizes, and a needle insertable and adjustable in said casing, said needle being longer than the casing and covered by the latter for substantially its entire length and having at least three shanks, said shanks being individually resiliently spaced apart in such a manner that the needle is maintained in any arbitrary position in the casing, said needle consisting of an integral resilient wire, the end portions of the needle constituting the two outer shanks, the intermediate shank being a double-folded portion of the wire, the elements of said double-folded portion lying close to one another, each of said shanks diverging in a different direction, each shank being of a different length, and one of the elements of the double-folded shank being fixed to the other element for a portion of its length.

3. A utensil for tobacco-pipes comprising a tubular, relatively thin-walled casing open from end to end and provided with integral flanges at both ends, said flanges being in the form of funnels and of different sizes, and a needle insertable and adjustable in said casing, said needle being longer than the casing and covered by the latter for substantially its entire length and having at least three shanks, said shanks being individually resiliently spaced apart in such a manner that the needle is maintained in any arbitrary position in the casing, said needle consisting of an integral resilient wire, the end portions of the needle constituting the two outer shanks, the intermediate shank being a double-folded portion of the wire, the elements of said double-folded portion lying close to one another, each of said shanks diverging in a different direction, each shank being of a different length and one of the elements of the double-folded shank being fixed to the other element for a portion of its length by being wound tightly around the other.

4. A utensil for tobacco-pipes comprising a tubular relatively thin-walled casing open from

end to end provided with integral flanges, one of the flanges being unsymmetrical, and a needle insertable and adjustable in said casing, said needle being longer than the casing and covered by the latter for substantially its entire length and having at least three shanks, said shanks being individually resiliently spaced apart in such a manner that the needle is maintained in any arbitrary position in the casing, said needle consisting of an integral resilient wire, the end portions of the needle constituting the two outer shanks, the intermediate shank being a double-folded portion lying close to one another, each of said shanks diverging in a different direction, each shank being of a different length, and one of the elements of the double-folded shank being fixed to the other element for a portion of its length.

5. A utensil for tobacco-pipes comprising a tubular casing of a circular cross-section open from end to end and provided with integral flanges at both ends, said flanges being in the form of funnels and of different sizes, and a needle insertable and adjustable in said casing, said needle being longer than the casing and covered by the latter for substantially its entire length and having at least three shanks being individually resiliently spaced apart in such a manner that the needle is maintained in any arbitrary position in the casing, said needle consisting of an integral resilient wire the end portions of the needle constituting the two outer shanks, the intermediate shank being a double-folded portion of the wire, the elements of said double-folded portion lying close to one another, each of said shanks diverging in a different direction, each shank being of a different length, and one of the elements of the double-folded shank being fixed to the other element for a portion of its length.

6. A utensil for tobacco-pipes comprising a tubular casing of an elliptic cross-section open from end to end and provided with integral flanges at both ends, said flanges being in the form of funnels and of different sizes, and a needle insertable and adjustable in said casing, said needle being longer than the casing and covered by the latter for substantially its entire length, and having at least three shanks, said shanks being individually resiliently spaced apart in such a manner that the needle is maintained in any arbitrary position in the casing, said needle consisting of an integral resilient wire, the end portions of the needle constituting the two outer shanks, the intermediate shank being a double-folded portion of the wire, the elements of said double-folded portion lying close to one another, each of said shanks diverging in a different direction, each shank being of a different length, and one of the elements of the double-folded shank being fixed to the other element for a portion of its length.
